UNITED STATES PATENT OFFICE

JOHN H. GRAYSON, OF LYNWOOD, CALIFORNIA, ASSIGNOR TO GRAYSON APPLIANCE COMPANY, LTD., OF LYNWOOD, CALIFORNIA, A CORPORATION OF CALIFORNIA

DESIGN FOR A CASING FOR A CONTROL MECHANISM FOR TIME CONTROLLED COOKING

Application filed October 3, 1932. Serial No. 45,195. Term of patent 14 years.

To all whom it may concern:

Be it known that I, JOHN H. GRAYSON, a citizen of the United States, residing at Lynwood, in the county of Los Angeles and State of California, have invented a new, original, and ornamental Design for a Casing for a Control Mechanism for Time Controlled Cooking, of which the following is a specification, reference being had to the accompanying drawing, forming part thereof.

The figure is a perspective view of a casing for a control mechanism for time controlled cooking showing my new design.

I claim:

The ornamental design for a casing for a control mechanism for time controlled cooking as shown.

In testimony whereof I have affixed my signature.

JOHN H. GRAYSON.
